CLAIM

We claim the ornamental design for a screw-together coffee press, as shown and described.

DESCRIPTION

FIG. 1 is a perspective view of a screw-together coffee press, showing our new design;

FIG. 2 is a front elevational view thereof; the rear elevational view being a mirror image thereof;

FIG. 3 is a left-side elevational view thereof; the right-side elevational view being a mirror image thereof;

FIG. 4 is a top plan view thereof;

FIG. 5 is a bottom plan view thereof; and,

FIG. 6 is a bottom perspective view thereof.
